Primary Examiner — George D. Kirschbaum*Assistant Examiner* — Maria J Edwards(74) *Attorney, Agent, or Firm* — Dority & Manning, P.A.(57) **CLAIM**

The ornamental design for a protective glove cuff, as shown and described.

DESCRIPTION

FIG. 1 is a front view of a protective glove cuff according to the present design;

FIG. 2 is a rear view of the protective glove of FIG. 1; and, FIG. 3 is a perspective view of the protective glove cuff of FIG. 1.

The broken lines in the figures represent unclaimed environmental subject matter illustrating the design in use and form no part of the claimed design.

1 Claim, 3 Drawing Sheets(56)
